UNITED STATES PATENT OFFICE.

MICHAEL PEKICH, OF PITTSBURGH, PENNSYLVANIA.

STEAM LOCOMOTIVE.

Application filed May 22, 1925. Serial No. 32,048.

My invention relates to improvements in steam locomotives, and particularly to means for reducing the noise and smoke incident to the operation thereof.

5 My invention has for one of its objects the provision of means whereby the exhaust from the locomotive cylinders is muffled or so controlled that it will be less audible than in the form of locomotives heretofore employed.

Another object of my invention is to provide means for reducing the amount of smoke which issues from the stack of a locomotive when fired.

15 Still another object of my invention is to simplify and improve generally the structure and operation of locomotives.

One form which my invention may take is shown in the accompanying drawing, 20 wherein Fig. 1 is a sectional view, in side elevation, of a locomotive embodying my invention, Fig. 2 is a view taken on the line 2—2 of Fig. 1, and Fig. 3 is a cross sectional view of a portion of the front end of 25 the locomotive.

It will be understood that my invention may be used in connection with other steam plants than those of the locomotive type, it being shown in connection with a locomotive 30 for convenience of description.

I have shown a locomotive which is provided with a boiler 10 and a fire box 11 which has a coal grate 12. Two door openings, 13 and 14, are provided for the introduction of coke and coal respectively. The 35 openings 13 and 14 are divided by a water-cooled connecting bar 15. A single door may be provided for both openings 13 and 14 or separate doors may be provided there- 40 for.

Above the grate bars 12 I provide a grate 16 which consists of water tubes that are connected to the water spaces in the boiler, in the usual manner, such as by tubes 17 at 45 their front ends and by tubes 18 at their rear ends. Fire bricks 19 are placed upon the tubes 17 so that the smoke and gas from the burning coal will have to pass between the tubes 16 that serve as a grate for the 50 coke. A series of tubes 20 is disposed above the coke grate 16 and communicates with the water spaces of the boiler through tubes 21 at one end, and through tubes 22 which 55 may have connection with the tubes 17. Bricks 23 surround the tubes 22 to prevent the passage of smoke and gas and to protect the

same from the heat, while bricks 24 form an arch which deflects the products of combustion rearwardly, in order that the smoke and gas will be more effectively consumed 60 and a greater amount of heat absorbed.

An opening 25 is provided in the side of the fire-box, which may be covered by a plate, if desired. When it is desired to clean the locomotive and particularly the 65 grate 16, a bar may be inserted through the opening 25 to raise the bricks 19 so that the unburned coke on grate 16 may be pushed between the tubes 17 and fall into the bottom of the fire-box. An opening 26 may 70 also be provided to serve as a peep-hole for detecting leaky tubes and inspecting conditions in the interior of the fire-box.

The locomotive is provided with the usual front end or smoke box 28 and stack 29. An 75 exhaust pipe 30 leading from the cylinders is directed upwardly toward the stack in the usual manner, but instead of exhausting directly through the stack, with the consequent noise incident to such procedure, espe- 80 cially when the locomotive is operated under heavy load, I direct such exhaust rearwardly to the fire-box, and for this purpose provide a pipe connection 31 at the entrance to which a valve 32 is placed. The valve 32 may be 85 operated from the exterior of the locomotive by a rock shaft 33 which extends through the side wall of the front end 28. It will be apparent that operation of the valve 33 will determine whether the exhaust will be con- 90 ducted directly through the stack or deflected through the pipe 31. The pipe 31 has connection with a fire tube 34.

Applying the invention to locomotives 95 equipped with superheater tubes as indicated at 35, I preferably remove one of the super- 100 heater tubes 35 and connect up the exhaust conduit 31 to the fire tube from which a superheater tube has been removed. If one fire tube does not have sufficient capacity I 105 may direct the exhaust steam through a plu- 110 rality of fire tubes. At its rear end, the fire tube 34 may have threaded connection with a tubular plug 36, such plug being provided with a flange 37 that may be bolted to a flange 38 which is carried by a manifold 39. The manifold 39 is provided with a series of nozzle openings 40 that are in alignment with as many of the fire tubes as may be de- 115 sired. The superheater tubes have connec- 120 tion with the steam dome and the cylinders, in the usual manner.

In addition to directing the cylinder exhaust into the fire box I may also cause the blower to exhaust thereto. A blower exhaust pipe 41 is connected to the cylinder exhaust pipe 30 and passes through the fire tube 34 to the nozzles 40 as in the case of the cylinder exhaust.

When the valve 32 is in position to prevent direct exhaust to the stack, such exhaust will pass to the fire box in the manner above described, and the noise thereof will be largely confined within the fire box and will be scarcely audible to those in the vicinity of the railroad tracks.

In addition to performing the function of a muffler, my device will assist in reducing the discharge of smoke and cinders from the locomotive stack, since the commingling of the steam and smoke at the entrance to the fire tubes will result in much of the solid matter being precipitated in the front end of the boiler from which it can be removed in the usual manner.

Direction of the steam to a point adjacent to the exit of the fire box avoids unnecessary cooling of the fire box, and particularly of the arch 24, thus permitting more complete combustion of the smoke and gas, than if the steam were admitted at a lower point in the fire box.

If desired, the exhaust steam from the air compressor (not shown) may also be directed rearwardly through the tube 34, such exhaust steam being indicated on the drawing as connected to the pipe 30 by a pipe

43. Inasmuch as the exhaust steam from the compressor may flow to the rear ends of the fire tubes while the locomotive is at rest, such steam will prevent excessive heating and burning out of the manifold 39 and its nozzles, since there is no water surrounding this manifold as in the case of the fire tubes.

I claim as my invention:

1. The combination with a steam locomotive having a fire-box, fire tubes, and a smoke box, of an exhaust pipe within the smoke box, a conduit leading from said pipe to the front end of one of said tubes, a manifold disposed in the fire-box and connected to the rear end of said tube, and forwardly-directed nozzles on said manifold, in longitudinal alinement with certain other fire tubes.

2. The combination with a steam locomotive having a fire-box, fire tubes, a smokebox, and a compressor, of an exhaust pipe in the smoke box for conducting steam from the locomotive cylinders and the compressor, a conduit leading from said pipe to the front end of one of said tubes, a manifold disposed in the fire box and connected to the rear end of said tube, and forwardly directed nozzles on said manifold, in longitudinal alinement with certain other fire tubes, the exhaust from the compressor serving to keep the manifold cool when no exhaust steam is passing from the cylinders.

In testimony whereof I, the said MICHAEL PEKICH have hereunto set my hand.

MICHAEL PEKICH.
